(57) CLAIM

The ornamental design for the exercise parallelette, as shown and described.

DESCRIPTION

FIG. 1 is a perspective view of a first embodiment of exercise parallelette according to the present invention; FIG. 2 is a front view of the exercise parallelette of FIG. 1; FIG. 3 is a back view of the exercise parallelette of FIG. 1; FIG. 4 is a first side view of the exercise parallelette of FIG. 1; FIG. 5 is a second side view of the exercise parallelette of FIG. 1; FIG. 6 is a top view of the exercise parallelette of FIG. 1; FIG. 7 is a bottom view of the exercise parallelette of FIG. 1; FIG. 8 is a perspective view of a second embodiment of exercise parallelette according to the present invention; FIG. 9 is a front view of the exercise parallelette of FIG. 8; FIG. 10 is a back view of the exercise parallelette of FIG. 8; FIG. 11 is a first side view of the exercise parallelette of FIG. 8; FIG. 12 is a second side view of the exercise parallelette of FIG. 8; FIG. 13 is a top view of the exercise parallelette of FIG. 8; and, FIG. 14 is a bottom view of the exercise parallelette of FIG. 8.
